No. 198

Spencer Richmond's Design for the Base & Legs of a Grandioseel Patent Aug. 22, 1848

Fig. 2

Fig. 1

Specification on file in Office of U. S. Patent, No. 3028

Des. 198

Apollos Richmond, Providence. R. I. Setters
Patent No 198- dated August 30 - 1818. (Assigned to
A. G. Barstow & Co.)

— — — — —
The Schedule referred to in these Letters Patent and
making part of the same.

— — — — —
To all Persons to whom these Presents shall come.

Be it Known, that I, Apollos Richmond of Providence, in
the County of Providence, and State of Rhode Island, have
invented or produced, a new and original design for the
base or bottom plate of an ordinary cylindrical air light

Stove, and that the following description taken in connection with the accompanying drawings hereinafter referred to, forms a full and exact specification of the same.

The figures of the accompanying plate of drawings represent my new design. Fig. 1 is a top view of the same, showing the ornamental carvings on the several mouldings and fig. 2 is a vertical section showing the contour of said mouldings.

My new ornamental design is confined mainly to the four legs a, a, a, a, which are cast solid with the bottom plate or base, and to the inner and outer ogee shaped mouldings designated respectively at b b b b & c c c c, in figs 1 & 2. The carving shown in detail in fig. 1 being continued all around said mouldings.

The inner moulding b b b b has all around its outer surface a succession of grooved, channelled or ribbed scrolls d, d, d, &c from each of which issues on the upper side two water leaves e, e, with sunken midribs and curled edges, and on the underside of each of said scrolls is a similar but smaller water leaf x, x, which is so curved or curled as to connect with the one on the underside of the adjacent scroll, the whole arrangement being as shown in fig. 2.

The outer moulding, c c c c, is ornamented similarly to the inner one, but the channelled or ribbed scrolls f f f f &c are much longer than those above referred to at d, d, d. Of these scrolls those on each side of each leg a, a, a, have three water leaves g g g issuing from their upper sides, the other scrolls beyond them having four such leaves so issuing and all of them having one leaf h on the underside, the leaves being like those before described but larger.

Each of the legs a, a, a, is ornamented with the four water leaves i i i i terminating in the two scrolls k, k.

3

Des. 198

and beneath said scroll a pellet - l - from which radiate
the several leaves m, m, m, &c. all as shown in Fig. 1.

Having thus described my new design, I shall
state my claim as follows.

What I claim as my invention or production,
and desire to have secured to me by Letters Patent is the
ornamental carvings on the base and legs (cast solid with
said base), of a cylindrical air tight stove, consisting of
the combination of scrolls, water leaves &c. as herein above
described and represented in the drawings
